E. W. WAYNERT,

FOLDING HARROW.

APPLICATION FILED NOV. 15, 1913.

1.110,846.

Patented Sept. 15, 1914.

UNITED STATES PATENT OFFICE.

ERIK W. WAYNERT, OF MASON, WISCONSIN.

FOLDING HARROW.

1,110,846.

Specification of Letters Patent. Patented Sept. 15, 1914.

Application filed November 15, 1913. Serial No. 801,102.

To all whom it may concern:

Be it known that I, ERIK W. WAYNERT, a citizen of Canada, residing in Mason, Bayfield county, Wisconsin, have invented certain new and useful Improvements in Folding Harrows, of which the following is a specification.

My invention relates to the type of harrow that is provided with wheels or vehicle attachments and having one section constructed and arranged to carry the other sections in driving to or from a field.

The object of the present invention is to provide improvements in this type of harrow, and the invention consists in the novel construction, combination and arrangement of parts, all as hereinafter described in detail, illustrated in the accompanying drawing and incorporated in the appended claims.

In the drawing—Figure 1 is a plan view of the middle, or vehicle section of a harrow embodying my invention. Fig. 2 is a section taken on line 2—2 of Fig. 1. Fig. 3 is a reduced plan view of a complete harrow of five sections minus the teeth or pins. Fig. 4 is a perspective view of the five sections folded up over the middle section, the latter having its wheels and runners projected to carry said middle section with its load of the other four sections.

In the several views 2, 3, 4, 5 and 6 represent metal bars made of iron tubes and having therein holes for bolt-eyes 7 fastened by nuts 8 to receive and clamp fast the usual harrow teeth 9 some of which are shown in Fig. 2.

The bars 2 to 6 are revolvably mounted in cross-bars 10, 11, 12, and 14 and are rotatable to place the teeth 9 in a substantially horizontal position and swing bearings for wheels 15 and 16 and runners 17 and 18 into a substantially vertical position, as the latter are shown in Fig. 4. The bearings for the 45 wheels are bent crank-like portions 19 and 20 at the ends of the tooth bar 2, while the bearings for the runners 17 and 18 are similarly formed parts 21, 22, 23 and 24 on the bars 5 and 6. The tooth bars 2 to 6 are 50 turned by means of cranks 25, 26, 27, and 28 secured axially to the bars and having their wrist-pins 29 pivoted to an actuating bar 30 which is moved longitudinally by means of a lever 31 secured to the bar 3 which 55 serves as the axis of rotation for said lever. The lever 31 is pivoted to the bar 30 at 32

and is provided with the usual small finger lever 33 operating a detent adapted to engage the notches in a quadrant 34, bolted at 35 and 36 to a bar 37 in which the bars 2, 3 and 4 are also journaled in any suitable manner. The five sections, labeled as 38, 39, 40, 41, and 42 are hinged together as at 43 and 44 by blocks having a mortise and tenon joint coupled by a bolt 45. The runners or shoes 17 and 18 are sheet metal stampings formed with upstanding lugs 46 and 47 serving as lower journal bearing members for the journal portions of the crank portions 21 to 23. The upper bearing members are blocks 48 and 49 which are slotted to pass over the journal portions of the bars 5 and 6 and are secured to the lugs 46 and 47 by means of transverse bolts 50 and 51.

In addition to simultaneously folding up the harrow teeth out of way as the wheels and runners are swung out to facilitate the transportation features of my invention, I have obviated the necessity of removing any part of the draft rigging for the sake of such transportation, by providing a jointed draw-bar composed of sections 52, 53, 54, 55, and 56 having at their ends mortises 57 and 58 and tenons 59, 60, and 61 held together by bolts 62. The sections 52 to 56 are each of a length corresponding substantially to the width of a section so that the draw-bar may be folded up with the sections as in Fig. 4 without necessitating its removal from connecting chains 63, 64, 65, and 66, connecting the sections with said draw-bar. The usual double-tree (not shown) is coupled to a ring 67 from which chains branch out to different sections, a chain 68 being shown extending to the middle section 54 and chains 69 and 70 to the sections 53 and 55.

71 is the usual clevis for making the chain and draw-bar connection. The construction of the middle section is also adapted for the side sections 38, 39, 41 and 42 for the purpose of tilting the teeth at different angles by merely omitting the wheels and runners from these sections, and where the harrow consists of one section 40, as well as when consisting of the five sections, swinging up the teeth at the same time as the wheels and runners are swung down obviates the necessity of such large 105 wheels and high runners as if the section 40 were to be made to clear the ground with

all the teeth therein projecting in their normal positions. The lever operation also becomes easier, and with the horizontal teeth projecting with their points rearwardly even a slight elevation of the middle section on its wheels and runners will enable it to clear uneven ground without getting caught or scratching up soil or lawn. All the parts being left intact ready for instant service, including the draw-bar 54, the usual troubles of hunting for separated parts the following season are obviated.

Obviously the construction serves equally as well for, say, a harrow of three sections, the side sections in that event leaning against each other and presenting when folded up for transportation to the storage shed substantially the same appearance as Fig. 4. The purpose of the runners 17 and 18 is to prevent the folded up structure to run against the draft animals in driving down grade, as would be apt to happen if wheels occupied the place of the runners. In other words, for this special purpose the load is lightened by means of wheels sufficiently for this special purpose and yet not sufficiently to cause accidents by the use of wheels.

Having thus described my invention, I claim as new and desire to secure by Letters Patent—

1. The combination with a plurality of harrow sections constructed and arranged

to fold up on a middle section, of wheels on said middle section, and means for simultaneously tilting said wheels, tilting the harrow teeth of said section into a substantially horizontal position and applying a moderate brake for said wheels, said wheels being normally supported on said harrow and tilted into position to support said harrow partly.

2. The combination with a harrow consisting of a middle section and side sections, of means for folding said side sections over said middle section, wheels carried by said middle section, braking means also carried by said middle section, and a lever constructed and arranged to throw the weight of said middle section upon said wheels and braking means, and to simultaneously tilt out of the way, the teeth of said middle section.

3. The combination with a harrow, of a series of rotatively mounted tooth-bars, a portion thereof having bent crank portions on which wheels and runners are journaled, the wheels and runners normally supported by said harrow, and a lever for rotating all of said tooth-bars simultaneously.

In testimony whereof I have hereunto set my hand in the presence of two subscribing witnesses.

ERIK W. WAYNERT.
